UNITED STATES PATENT OFFICE.

GERARD HUBERT GERAERDTS, OF NEW YORK, N. Y.

WINDOW-SILL.

977,946.

Specification of Letters Patent.

Patented Dec. 6, 1910.

Application filed June 26, 1909. Serial No. 504,506.

To all whom it may concern:

Be it known that I, GERARD HUBERT GERAERDTS, a citizen of the United States, and a resident of the city of New York, borough 5 of Manhattan, in the county and State of New York, have invented a new and Improved Window-Sill, of which the following is a full, clear, and exact description.

The invention relates to building materials and its object is to provide a new and improved window sill, preferably made of cement, concrete or other cementitious material, and arranged for support at the ends only, so that the middle portion is unsupported 10 and hence the window sill is not liable to crack in case the building settles.

Another object of the invention is to provide means for preventing rain or other water passing over the window sill from 15 flowing onto the wall of the building.

For the purpose mentioned, the sill is formed at the ends with integral abutments built in the wall, the abutments forming between them a recess on the under side of the 25 sill, so that the sill is unsupported between the abutments. The sill is also provided at the under side and at the portion projecting beyond the face of the wall with a longitudinally-extending groove, to cause the 30 water to drip off the outer end of the sill without flowing onto the wall of the building.

A practical embodiment of the invention is represented in the accompanying drawings forming a part of this specification, in which similar characters of reference indicate corresponding parts in all the views.

Figure 1 is a front elevation of a portion of the wall of a brick building, provided 40 with my improved sill; Fig. 2 is a perspective view of the sill; Fig. 3 is a similar view of the sill inverted; and Fig. 4 is a cross section of the sill as applied on the wall of the building.

The window sill A is preferably made of cement, concrete or other similar material, placed in a plastic condition into a suitable mold for the material to set, harden and to conform to the shape of the mold, the finished window sill being subsequently built in the wall B of the building, as shown in Fig. 1 and as hereinafter more fully described.

The body of the window sill A is provided at its ends with the integral abutments C, C, depending from the under side of the

body and projecting above the upper face thereof, the abutments C, C being built into the wall B in such a manner that the under faces C' of the abutments C, C rest on the 60 corresponding course of the bricks or other building material of which the wall B is made, while the bricks, for the sides of the window opening, rest on the upper faces C² of the abutments C, C. By arranging the 65 abutments C, C in the manner described, the under face of the sill appears with a recess D extending between the opening faces C', C' of the abutments C, C, and as the said abutment under faces C', C' rest on a course 70 of the bricks, it is evident that the portion of the sill between the abutments C, C is unsupported, and hence if the wall B should settle at either abutment the sill settles with it at this end but is not liable to crack as it 75 is unsupported between the abutments.

It is understood that if the sill is supported at its under portion throughout its length, and the wall settles at one end of the sill, then the latter is liable to crack. 80

The sill is of a width exceeding the thickness of the wall B, the inner side of the sill being approximately flush with the inner face of the wall, while the outer portion of the sill projects a desired distance beyond 85 the outer face of the wall B. The outer projecting portion of the sill is flush at the under side E with the under faces C', C' of the abutments C, C, and in the said under side E is formed a longitudinally-extending 90 groove E', to cause the rain or other water to drip off the outer end of the sill without flowing onto the wall of the building, as will be readily understood by reference to Fig. 2. 95

The inner upper face of the sill is provided with a raised portion F, extending from one abutment C to the other, and flush with the upper face C² thereof, as plainly indicated in Fig. 2, so that a proper support is had for the window casing set in the window opening and resting on the sill A. The outer ends of the upper faces C² of the abutments C, C terminate a distance from the outer side of the sill, that is, each 100 face C² of the abutments corresponds in width to the thickness of the wall B, as plainly indicated in Fig. 4. The upper face G of the sill, extending between the faces C² and the raised portion F, is inclined downwardly and outwardly, so that the rain water is readily drained off from 110

the upper surface of the sill and passes down the front side thereof, to finally drop off at the lower end, as previously explained, the water not being liable to flow onto the wall 5 B, as the longitudinal groove E' prevents the flow of the water on the under side of the projecting portion of the same.

The sill shown and described can be readily formed in a correspondingly shaped 10 mold, and when properly set and hardened the sill can be conveniently built in the wall of the building without danger of the sill cracking in case the building settles.

The sill shown and described can be 15 cheaply manufactured and requires no hand work for trimming as is the case with the usual stone sills now generally used.

Having thus described my invention, I 20 claim as new and desire to secure by Letters Patent:

A window sill of plastic material com-

prising a body, having on its upper face at the inner side thereof a longitudinal flat ledge provided at each end with an angular portion, the outer edge of the ledge and the angular portion being flush with the sides and ends of the sill, the upper face of the sill between the ledges sloping outwardly and downwardly, the under face of the sill having at its outer side a ledge having a flat surface and provided with a longitudinal groove, spaced apart from the outer edge and having also ledges at the ends extending to the opposite side of the sill, for the purpose specified.

In testimony whereof I have signed my name to this specification in the presence of two subscribing witnesses.

GERARD HUBERT GERAERDTS.
